PAINTING MASK FOR WHEELS

Fred A. Neuman, Lansing, Mich., assignor to General Motors Corporation, Detroit, Mich., a corporation of Delaware

Application July 23, 1931, Serial No. 552,681

12 Claims. (Cl. 91—65)

This invention relates to the art of painting wheels and has particular reference to the painting of the felly.

In prior practice where it is desired to paint the felly with a paint having a different color than the paint on the spokes, it has been customary to wrap paper around the spokes and then spray the felly with the usual paint gun. The paper would prevent the paint from contacting with or adhering to the spokes and when the paper was removed, it would leave the spokes in their original color with only the felly painted. This method of using paper was found to consume a great deal of time and was expensive. The present invention aims to provide a device which will enable the painting of the felly to be accomplished in a much less time and at less cost.

The object of the invention is accomplished by placing on one side of the wheel a mask which has a central ring member provided with slideable radiating fingers to which are attached semi-cylindrical covering members which extend over the spokes. A similar mask is placed on the opposite side of the wheel and has semi-cylindrical covering members which mate with the covering members of the first-mentioned mask completely to enclose the spokes adjacent the rim. The slideable fingers are drawn toward the center of the masks by means of resilient bands and, in applying the masks to the wheel, a cam acts on the fingers to force them radially outward to cause the spoke covering members to abut against the interior of the felly. Both of the masks are readily removable and in use the wheel is turnably mounted on a shaft revolvably mounted in an upright. One of the masks is permanently mounted on the shaft and receives the wheel while the second mask is positioned over the wheel after it is in place on its mount.

On the drawings:

Figure 1 is a vertical section through a wheel and the masks taken substantially on the line 1—1 of Figure 2, the parts being shown in position on the mount.

Figure 2 is a front elevation taken substantially on the line 2—2 of Figure 1 with parts broken away and shown in section.

Figure 3 is a section on the line 3—3 of Figures 1 and 2.

Referring to the drawings, the numeral 2 indicates a suitable upright mounted on the floor and having a swiveled head 4 at its end. The head has the bearing 6 and the oil groove 8

closed by a cap 10. In the bearing, there is rotatably received the shaft 12 having the bore 14.

At its forward end, the shaft 12 terminates in an enlarged flange 16 provided with the studs 18 which fit into the bored portions 20 of a holder 22. The holder has a stepped bore 24 in which there is received the plunger 26. The plunger extends through the bore 14 and is forked at its rearward end to receive the cam 28 mounted in the fork by means of the pivot pin 30. A handle 32 operates the cam.

At its forward end, the plunger 26 terminates in a head 34 received in the bore 36 of a holding member 38. The holding member 38 terminates in a neck 40 and a head 42, the purpose of which later will be described. The holding member 38 is threaded at its inner end and receives the externally threaded nut 44 through the bore of which the plunger 26 passes. A spring 46 is confined between the head 34 and nut 44 and a second spring 48 is confined between the nut and the shoulder at the end of the stepped bore 24. The springs 46 and 48 are for the purpose of resiliently holding the masks and wheel on the mount.

The wheel is indicated as a whole at 50 and comprises the felly 52, the spokes 54 and the hub member 53. On the inner portion of the wheel, a painting mask 55 is mounted while on the outer side, the similar painting mask 56 appears. The details of both masks are substantially identical and a description of one will suffice for the description of both.

Each mask comprises the central ring member 58 which is stepped as indicated at 60, the innermost portion of the stepped member abutting against the wheel. In the web portion 62 of the stepped portion 60, there is provided a plurality of openings 64 for the reception of the ends of fingers 66 held on to the interior of the plate 58 by means of the U clips or brackets 68. To the outer or free ends of the fingers 66, there are attached to the inside thereof the hooks 70 and on the outside thereof the spring clips 72 and spring fingers 74. The parts 70, 72 and 74 are secured to the fingers 66 by means of the rivets 76. An elastic or rubber band 78 passes through the hooks 70 and resiliently urges or pulls the fingers 66 and the parts attached thereto inwardly of the mask 55 or 56.

Secured to the end of each clip 72 by means of the rivets 80 is a semi-cylindrical covering member 82, which extends over and covers the spokes 54. The end or tip of each covering

member 82 adjacent the felly 52 is provided with a plurality of buttons or projections 84 which strike against the portion of the felly immediately adjacent the spokes. The purpose of these 5 projections is to allow the paint from the paint gun to reach the portions of the felly very close to the spokes. The springs 74 have their ends 86 contacting with the ends of the clips 72 and constantly urge the covering members 10 82 toward the spokes when the masks are in position.

The inner mask 55 is secured to the flange 88 formed on the mounting member 22. The flange 88 has recesses formed therein at spaced 15 points slidably to receive the head of a stud or rivet 90 secured to the ring 58 as at 92. The ends of the recesses are closed by the cap 94 and a coil spring 96 is mounted between the head of the stud 90 and the cap and resiliently urges the stud away from the flange 88. The purpose of this construction is to form a flexible and resilient support for the mask, to assure a tight fit of the mask on the wheel, and to allow for slight inaccuracies in workmanship. 20 The outer mask 56 is similarly mounted on a cup-shaped holder or retaining member 98 and is held thereon by similar studs 90 and springs 96.

A swingable hook 100 is pivotally mounted on 30 the holder 98 by means of the rivet 102, the hook end of which is adapted to be swung into and out of engagement with the neck 40 and head 42. This is clearly shown in the full and dotted outlines in Figure 2.

35 The holder member 98 has the annular flange 104 which corresponds to the flange 88 on the supporting member 22. Both of these flanges are provided with annular or conical cam surfaces 106 which act on the ends of the fingers 40 66 to press them outwardly against the tension of the resilient bands 78. This action occurs when the masks are on the wheel and are held in place by means of the head 42, hook 100 and the cam 28 and its associated mechanism. 45 These cams will force the covering members 82 against the inner periphery of the felly 52 and thereby assure the covering of the spokes adjacent the felly to prevent the access of paint to the spokes.

50 The covering members 82 are constructed so that they overlap slightly at their edges as shown at 108 in Figure 1. One of the covering members 82, preferably the inner underlapping one, has secured thereto angle irons 110. The purpose of these irons is to limit the overlap of 55 and to prevent the two covering members from contacting with the spokes at their innermost ends. The angle irons are secured such as by welding at 112 and the flange 114 thereof is 60 adapted to receive the end of the overlapping covering member 82.

If desired, a rubber head 116 on a stud 118 secured as at 120 to the retaining member 98, may be used to position the mask 56. The head 65 116 fits in the opening 20 in the wheel.

The operation of the device is as follows: assuming that there is no wheel on the mount or holder 22, the operator takes a wheel 50 and places it on the mount. The mask 55 is 70 already in place and the spokes 54 of the wheel are fitted into the covering members 82. The outer mask 56 is then positioned on the wheel with the covering members 82 positioned over the spokes and overlapping the covering member 75 82 of the mask 54. The hook 100 is then

swung into engagement with the neck 40 and the cam 28 then swung from the full line position to the dotted line position of Figure 1. This will draw the retaining member 98 inwardly against the tension of the springs 96 and also depress the springs 96 of the inner mask 54. The cams 106 will at the same time come into action and force the fingers 66 radially outwardly to force the covering members 82 tightly against the inner periphery of the felly 52. The notches or buttons 84 now will be tightly pressed against the felly and the device is ready for the paint gun. The paint is now sprayed on the interior of the felly and the wheel rotated at the same time. After the painting operation has been completed, the cam 28 is swung to the full line position which will allow the hook 100 to be swung free of the neck 40 and permit the renewal of the outer mask 56. The wheel may now be taken from the mount and a new wheel inserted.

I claim:

1. In the art of painting spoked wheels, means for covering the spokes and hub of the wheel preparatory to painting the felly, comprising 100 a mask for covering the spokes at one side of the wheel, and a second mask for covering the spokes at the other side of the wheel, said two masks surrounding the spokes only at the felly so that no paint will be applied to the spokes 105 while the felly is being painted.

2. In the art of painting wheels, means for surrounding the spokes during the painting of the felly, comprising a mask for one side of the wheel, said mask including a plurality of semi-cylindrical members covering the spokes, and a mask for the other side of the wheel, said second mask including a plurality of semi-cylindrical members complementary to the first members, said members surrounding the spokes only 110 at the felly.

3. In the art of painting wheels, means for covering both sides of the spokes only during the painting of the felly, comprising a mask for one side of the wheel, said mask including a 120 plurality of semi-cylindrical members covering the spokes, springs for pressing said members against the spokes, a mask for the other side of the wheel, said second mask including a plurality of semi-cylindrical members complementary to the first members, and springs for pressing said members against the spokes, said members surrounding the spokes only at the felly.

4. In the art of painting spoked wheels, a mask for covering the spokes of a wheel comprising a plate, a plurality of covering members connected to said plate, said members partially surrounding and covering a portion of each of the spokes only at the felly.

5. In the art of painting spoked wheels, a 130 mask for covering the spokes of a wheel comprising a plate, a plurality of covering members connected to said plate, said members partially surrounding and covering a portion of each of the spokes only at the felly, and means resiliently pressing said members against the spokes when the mask is in position on the wheel.

6. In the art of painting spoked wheels, a mask for covering the spokes of a wheel comprising a plate, a plurality of members for 140 partially surrounding and covering a portion of each of the spokes only at the felly, one member for each spoke, means for attaching said members to the plate, and means resiliently pressing said members against the spokes.

7. In the art of painting wheels, a means to cover the spokes of the wheel during the painting of the wheel comprising a mask having a central plate, a plurality of fingers slidably mounted on said plate, and spoke covering members, one mounted on each finger and adapted to cover the spokes at the felly. 5 80
8. In the art of painting wheels, a means to cover the spokes of the wheel during the painting of the wheel comprising a mask having a central plate, a plurality of fingers slidably mounted on said plate, a spoke covering member mounted on each finger and adapted to cover the spokes at the felly, and means resiliently urging said spoke covering members against the spokes when the mask is in position. 10 85
9. In the art of painting wheels, a means to cover the spokes of the wheel during the painting of the wheel comprising a mask having a central plate, a plurality of fingers slidably mounted on said plate, a spoke covering member mounted on each finger and adapted to cover the spoke at the felly, and means resiliently urging said fingers toward the plate. 15 90
10. In the art of painting wheels, a means to cover the spokes of the wheel during the painting of the wheel comprising a mask having a central plate, a plurality of fingers slidably mounted on said plate, a spoke covering member mounted on each finger and adapted to cover the spokes at the felly, hooks secured to the fingers, and means engaging the hooks and resiliently urging said fingers toward the plate. 20 95
11. In the art of painting wheels, a means to cover the spokes of the wheel during the painting of the wheel comprising a mask having a central plate, a plurality of fingers slidably mounted on said plate, a spoke covering member mounted on each finger and adapted to cover the spokes at the felly, hooks secured to the fingers, and means engaging the hooks and resiliently urging said fingers toward the plate. 25 100
